WEIR RING AND DOWNCOMER ASSEMBLY
FOR DISTILLING COLUMNS

Theodore O. Wentworth, Cincinnati, Ohio, assignor to The Vulcan Copper & Supply Co., Cincinnati, Ohio, a corporation of Ohio

Application December 16, 1936, Serial No. 116,109

3 Claims. (Cl. 261—114)

This invention relates to weir ring and downcomer constructions for distilling columns in which the weir ring comprises a shallow member adapted to rest upon the upper face of an appropriate one of the plurality of trays held in spaced relation within a distilling column, the weir ring surrounding an opening in the tray, and the downcomer elements comprise pipes having flanges which are connected to bracket arms projecting from the weir ring.

The invention will be described with reference to the accompanying drawings in which:

Figure 1 is a view in elevation, partly broken away, of a distilling column, and showing certain interior members in dotted lines, comprising a plurality of superposed shell sections each enclosing a plurality of plates which may be of the bubble cap type or of any other suitable type.

Figure 2 is an enlarged vertical section through the lower portion of the column and partly broken away to show the interior of two shell sections and the supporting base.

Figure 3 is a top plan view of one of the plates, illustrating more particularly one type of downcomer assembly for run-off of the reflux liquid from one plate to the next lower plate.

Figure 4 is a view in side elevation of the plate shown in the preceding figure, with the downcomer assembly applied thereto, the seal cup being low the assembly being shown in vertical section.

Referring to Figs. 1 to 3 inclusive of the drawings, it will be seen that the upper and lower portions of a distilling column are shown in elevation with certain interior members indicated in dotted lines. The heavy supporting ring 1 carries the base cylindrical shell 2. The ring 1 is formed with an upper horizontal flange 1x which is, in practice, bolted to the lower horizontal flange 2x of shell 2. These flange members hold 40 between them a dished base plate 3 for shell 1, which will be of very heavy construction, since it will in the present embodiment, act as the primary supporting member for the horizontal plates of the column. Another suitable construction is 45 the use of a flat bottom plate, backed by a heavy steel plate, or suitable level foundation, capable of supporting the load.

Plate 3 is formed with a flange 3x lying between the flanges 1x and 2x and bolted thereto by means of bolts, one of which is shown at 4, Fig. 2. A suitable packing ring or rings may be employed, as indicated at 5, Fig. 2.

Welded to the upper surface of plate 3 are a plurality of seat members 6 which may be located 55 at the positions indicated at 6x. Thus, in the

present embodiment, eleven seats are employed. Each seat at its top is provided with a recess having a true horizontal base to receive the primary supporting posts 7 which may be tubular in form, as shown in Fig. 2. When the posts 7 are tubular, each post may receive at its top a horizontally flanged cap member 8 provided with an upwardly extending nipple 8x adapted to pass through an aperture formed in the first tray 9 at the appropriate one of the positions 6x.

As stated above, the plates may support bubble caps or the plates themselves may be perforated to allow contact directly of vapors rising through perforations to the liquid supported on top of the plates. In Fig. 2 of the drawings, bubble caps are 15 shown at 10.

Each nipple 8x is received within the recess of a spacer post 11, preferably formed with a base flange and with a top flange 11x upon which the succeeding tray as, for example, 12, Fig. 2, is supported in true horizontal position, each spacer post 11 being provided above flange 11x with a nipple 11xx which enters the base recess of a superposed spacer post, as, for example, 13, Fig. 2.

In some cases, particularly those plates between which fall the flanged joints of adjoining column sections, it may be desired to provide a longitudinal adjustment for the spacer posts and to that end, the post 13 shown completely illustrated in Fig. 2, is sectional. The lower section 30 is formed with a threaded axial aperture to receive the threaded stem of the upper section which bears the numeral 13x and it is the upper section which is formed with a flanged seat to receive the overlying tray indicated at 14. By 35 relative rotation of the two post sections 13, 13x, an adjustment in length may be secured. Section 13x is formed with an upwardly projecting nipple to pass through the tray 14 and in turn to receive the superposed post for an overlying tray. This arrangement will be continued for the support of the superposed trays until the top of the column is reached, and the number of cylindrical shells and the number of the trays in each one may be varied at will, in accordance with the required conditions.

While the load is taken by the collinear posts after final field assembly, the trays may be supported in shipment by continuous rings (not shown) underlying the trays and carried by the 50 cylindrical sections or by a plurality of lugs such as shown in Fig. 2. In that figure the upwardly extending lug 22 is carried by a short vertical plate or bracket arm 23 having a threaded stem which passes through the shell and which has 55

secured to the end thereof a nut 26, washers being preferably used to surround the threaded end both interiorly and exteriorly of the shell section. Each shell, at its top, will be provided with an 5 outwardly extending horizontal flange 15 upon which is superposed the lower flange of a surmounting shell section like the flange 2x of shell section 2 and therefore bearing the same numeral. Likewise, a packing ring or gasket 10 10 may be imposed between the two. Flange and heavy clamping rings 16 may be employed to directly receive the bolts 4.

It will be seen from the above a plurality of 15 spacer posts are prepared with each one identical in dimensions with the others. By an arrangement of plugs and holes, screw threads, key ways, or other suitable mechanical designs, these posts are arranged to set upon the plate immediately 20 above the posts beneath and in this way the weight of each is transmitted downwardly through the successively lower posts to the heavy base plate at the bottom of the column which may in some cases be supported on the floor. By 25 reason of the uniform dimensions of the posts, it is obvious that every plate above the lowest plate will be parallel with the lowest plate and with each other, and that by proper levelling of the column as a whole, all plates will be absolutely level. This has not been the case in columns of 30 previous designs in which the plates were joined to the column shell itself.

A feature of my invention is the construction 35 of the down pipes which heretofore have been fastened in by various modifications of the standard brazing or welding technique. As shown in the drawings, I have separated the two functions of the downcomer pipe which are: (1) a weir to maintain a constant level of liquid 40 on the plate and allow overflow from the plate, and (2) a down pipe carrying this liquid to the plate beneath and suitably trapped in the liquid 45 on the plate beneath. This downcomer assembly is in two parts—a circular, ovaloid, or other suitably shaped weir arrangement enclosing a space and machined on top and bottom with parallel faces so that the edge will everywhere be the same distance above the plate.

Referring to Figs. 3 and 4 of the drawings, the 50 weir ring 17 is ovaloid in shape and is formed

with a plurality of inwardly projected bracket arms 18 provided with holes for the bolts (not shown) which are applied to the flanges 19 of the downcomer pipes 20. The downcomer pipes will be provided with clips 21 for securing thereto 5 the seal cup 22 in the case of the lowermost plate of the column. In all other cases the seal is provided by the liquid on the next lower plate.

This assembly may be cheaply constructed and has the advantage that it requires no brazing 10 to the plate and therefore no heating of the plate which tends to distort the copper sheet.

Having described my invention, what I claim and desire to secure by Letters Patent, is as follows:

1. In a distilling column, a plurality of trays held in spaced relation within the column and a downcomer assembly comprising a weir ring, the 15 weir ring being mounted on the appropriate tray and having projected bracket arms, and a plurality of downcomer pipes having flanges, and means connecting the flanges of the downcomer pipes to the bracket arms of the weir ring, the 20 said pipes communicating with apertures in the tray at that area bounded by the weir ring. 25

2. In a distilling column, a plurality of trays held in spaced relation within the column and a downcomer assembly comprising a weir ring, the 30 weir ring comprising a shallow member adapted to rest upon the upper face of an appropriate tray and to surround an opening therein, a plurality of bracket arms projected inwardly from the 35 weir ring, a downcomer pipe having at its upper end a laterally projected flange, the flange being apertured and contacting with the lower face of the tray and surrounding the opening therein, and bolts detachably connecting the downcomer pipe flange and the bracket arms of the 40 weir ring. 45

3. In a distilling column, a weir ring and downcomer pipe construction, in accordance with claim 2, in which the weir ring is ovaloid in form and is provided with two sets of bracket arms and the tray is formed with two openings, each opening being bounded at its underface by the flange of a downcomer pipe, each flange being bolted to an appropriate set of bracket arms of the 45 weir ring.

THEODORE O. WENTWORTH.
